UNITED STATES PATENT OFFICE.

ALEXIS HAROLD ROSS, OF WAUKON, IOWA.

COMBINED STOVE-PIPE HEATER AND VENTILATOR.

SPECIFICATION forming part of Letters Patent No. 395,999, dated January 8, 1889.

Application filed June 29, 1888. Serial No. 278,514. (No model.)

To all whom it may concern:

Be it known that I, ALEXIS HAROLD ROSS, of Waukon, in the county of Allamakee and State of Iowa, have invented certain new and useful Improvements in a Combined Stove-Pipe Heater and Ventilator; and I do hereby declare the following to be a full, clear, and exact description of the invention, such as will enable others skilled in the art to which it pertains to make and use it, reference being had to the accompanying drawings, which form part of this specification.

My invention relates to an improvement in a combined stove-pipe heater and ventilator; and the objects of my invention are to form in the lower part of the heater an air-chamber, into which the air is admitted, and which then escapes through the vertical pipes, which are heated by the escaping products of combustion; to place inside of the heater a hot-air chamber and deflector, which is connected at its lower end with the air-chamber inside of the heater, and is provided at its upper end with pipes for the escape of the heated air, and to connect to the heater a ventilating-pipe which will take all of the foul air from the bottom of the room and discharge it directly into the stove-pipe.

Figures 1 and 2 represent vertical sections of a device embodying my invention, taken at right angles to each other.

A represents the stove-pipe, and B the heater, which is placed between the two sections of the pipe A, and through which heater all the products of combustion must pass. In the lower end of this heater B is formed an air-chamber, C, and to this chamber is connected, at one side, the air-pipe D, which is provided with a register, E, and a damper, F. The lower end of this pipe D is to be made to extend to the outside air, so that when the damper F is open and the register E is closed pure air will be admitted to the chamber C, heated, and then discharged into the room. Should heat more than fresh air be desirable, as in very cold weather, the damper F will be closed and the register E opened, and then the cool air will be taken from the bottom of the room, heated, and discharged back into the upper part of the room. When the

damper F is open, the register E should be closed, and when the register is open the damper should be closed. The air admitted to the chamber C rises through the pipes G, in which it is heated, and escapes from the 55 pipes into the top of the room.

Placed inside of the heater B is a hot-air chamber and deflector, H, which is located directly in the line of the upward passage of the products of combustion, and which serves 60 to deflect the products outward toward the sides of the heater B and around the pipes G. The heater B throws off its heat into the room and the pipes G absorb a great portion of the escaping heat and utilizes it in heating the 65 air which is passing through them. Were it not for this chamber H the products of combustion would pass directly through the heater B, and then the greater portion would be allowed to escape up the chimney. Connected to the lower end of this chamber H and to the top of the chamber C are the pipes G', through which a portion of the air admitted into the chamber C passes into the chamber H to be heated, and from the top of which 75 chamber H this heated air escapes through the pipes J into the top of the room.

Extending upward from the bottom of the room and connected with the upper end of the heater B is the pipe L, which is provided 80 with the damper O. When the damper O is opened, the foul air in the room is taken through the lower end of the pipe L, discharged directly into the upper portion of the heater B, and from thence it is discharged 85 into the stove-pipe. This pipe L is connected to the upper end of the heater B, so that the cold air which is being taken from the bottom of the room will not serve to diminish the amount of heat which is being absorbed by 90 the pipes G, G', and J and the chambers C H, as would otherwise be the case if the pipe L were connected to the heater near its bottom. Being connected to its top, the cold air from the bottom of the room is discharged into the 95 heater at that point where the heat is no longer exerting any great amount of effect.

It will be seen from the construction here shown and described that this heater can be made to take the place of a stove where only 100

a moderate amount of heat is necessary, and can be made both to heat and to ventilate a room most perfectly.

Having thus described my invention, I

5 claim—

The combination of the stove-pipe, the air-chamber located in its lower end, the pipe for admitting air to this chamber, the pipes G, which extend from the top of the chamber

o through the heater, the chamber H, located

in the center of the heater and provided with the pipes G' J, and which chamber H receives its air from the chamber C, substantially as described.

In testimony whereof I affix my signature 15
in presence of two witnesses.

ALEXIS HAROLD ROSS.
